Patented Mar. 28, 1922.

UNITED STATES PATENT OFFICE.

ARTHUR W. CAPS, OF TOPEKA, KANSAS, ASSIGNOR TO THE PIERSEN MANUFACTURING CO., OF TOPEKA, KANSAS, A CORPORATION OF KANSAS.

TIMER CASING.

1,410,649.

Specification of Letters Patent. Patented Mar. 28, 1922.

Application filed June 16, 1919. Serial No. 304,403.

To all whom it may concern:

Be it known that I, ARTHUR W. CAPS, a citizen of the United States, residing at Topeka, in the county of Shawnee and State 5 of Kansas, have invented certain new and useful Improvements in Timer Casings; and I do declare the following to be a full, clear, and exact description of the invention, such as will enable others skilled in 10 the art to which is appertains to make and use the same, reference being had to the accompanying drawings, and to the letters and figures of reference marked thereon, which form a part of this specification.

15 This invention relates to timers, and more particularly to a device of that character for timing the ignition spark of a multiple cylinder explosion engine.

One of the objects of the invention is to 20 construct the parts of the timer so that they may be assembled by unskilled workmen and without the necessity for employing jig or other especially constructed assembling tools.

25 It is also the purpose of this invention to provide a timer which may be readily disassembled for inspection or repairs and in such manner that worn-out parts may be replaced without special skill.

30 The invention also contemplates the provision of means whereby the parts subjected to wear may be of standard construction and interchangeable so that the 35 number of parts which the dealer will have to carry in stock will be reduced to a minimum.

In the drawings,

Fig. I is a perspective view of a timer casing with an insulated ring and contacts 40 carried thereby, and constructed in accordance with my invention.

Fig. II is a sectional view on the line II—II of Fig. III, looking in the direction of the arrows.

45 Fig. III is a sectional view on the line III—III of Fig. II, looking in the direction of the arrows.

Fig. IV is a detail perspective view of one of the insulating blocks constituting a 50 segment of a ring, and

Fig. V is a detail view of one of the contacts and the means for securing it to the casing.

Referring now to the drawings by numerals of reference:

1 designates a shell or housing preferably of sheet metal which may consist of a spinning and which is here shown as substantially in the form of a truncated cone, the annular flange 2 of which is provided with 5 a plurality of equi-distant holes or openings 3. The openings are here shown as 90° apart to receive the contact fastening devices as the device is adapted for a four cylinder engine. The insulating ring is 60 shown as consisting of a plurality of segmental blocks 4 preferably molded into form and provided terminally with offsets or shoulders 5 and 6 to receive the contacts which also serve as clamping devices for the 65 segments. The outer face of each segment is recessed at 4' to provide feet 5' and 6' opposite the offsets for the purpose presently described.

70 By reference to Fig. II it will be observed that the segmental blocks 4 are spaced apart and are bridged by channel contacts 7, the ends 8 and 9 of which overlap and engage the offset portions 5 and 6, and that the parallel sides 10 and 11 of the 75 channels overlap the sides of the blocks 4 so that the blocks will be clamped in place when tension is applied to the eye bolts 12 which serve to hold the contacts in place and may constitute binding posts. The 80 heads 12' of the eye bolts practically fill the space between the flanges 10 and 11 of contacts 7 so that the segments and contacts are held in perfect alignment by the 85 bolts.

90 By reference to Fig. V it will be observed that the eye bolts 12 are fastened to the parallel sides 10 and 11 by pins 13, thereby permitting the eye bolts to have a 95 swivel motion with respect to the contacts so as to insure proper setting of the contacts 7 upon the segments 4, even though the openings 3 are not spaced to very close limits of accuracy. The eye bolts 12 project through the openings 3 and are adapted 100 to receive insulating filler washers 14 which preferably are of the same diameter as and seat within the openings 3 whereby said 105 filler washers may rest upon the outer edges of the segments which are of sufficient length to project slightly beyond the open-

ings 3, and thereby present shoulders upon which the washers may seat.

In the present embodiment of my invention I also contemplate applying bearing washers 15 and nuts 16 to the bolts 12 so that when the nuts are tightened they force the washers against the outer face of the casing flange and draw the contact members 7 against the segment blocks 4, thereby 10 drawing the blocks against the inner face of the flange to clamp the blocks to the flange and form a firm ring of alternate conductive and nonconductive sections. The filler washers 14 are thinner than the flange 15 2 of the casing, so that when the parts are in the position shown in Figs. I and II, they rest within the holes or openings 3 and the bearing washers 15 contact with the outer surface of flange 2. Consequently, 20 the parts are held rigid and there is no radial play of the contacts as might occur if the bearing washers 15 were held against the filler washers 14.

The movable contact is carried by a shaft 25 18, geared to the main engine shaft (not shown), and may be of any preferred construction, but is here shown to consist of a lever 17 pivoted on a pin 19, in a yoke 20 on a collar 20' that is fixed on said shaft. 30 The lever 17 carries a roller 21 at one end which is moved to contact with the ring 4—7 by a spring 22 that is connected with the inner end of the lever and with an arm 23, also projecting from said collar. With 35 this arrangement, when the shaft revolves within the stationary housing, the roller 21 will contact alternately with the nonconductive segment blocks 4 and with the conductive contact members 7.

40 It will be apparent that all of the contact members 7 and their fastening devices may be of like construction as may also the segment blocks 4, so that they are interchangeable and may be quickly assembled 45 without specific arrangement in the casing. Since the segment blocks 4 may be molded, liability of their absorbing moisture and thereby warping out of shape will be materially reduced. Some molded insulation 50 products are somewhat brittle and as there may be slight variations in the casings, I have provided the segments 4 with the outer recesses 4' so that the contacts 7 can be drawn down tightly onto the segments and 55 press the feet 5' and 6' against the flange 2 without danger of breaking the segments.

A ring may thus be formed, having a substantially true bearing circle irrespective of possible irregularities in the housing frame, 60 thereby obviating the necessity for strict accuracy in the construction of the housing, with the resultant saving in manufacturing and inspection.

Since it is contemplated to mold the segments 4, the product will be uniform, re-

quiring little inspection and low tool up-keep expense after the dies which form them are made.

I prefer to utilize the washers 14 and 15 as separate flat washers rather than mold 70 them integral because these washers are of standard size and can be purchased upon the open market, the advantage of this being apparent as it reduces the number of special parts which the dealer would have 75 to carry for repairs, as well as the reduction of the initial cost since no special machine would have to be used in their manufacture.

It will be apparent from the foregoing 80 that the device can be cheaply constructed and that it may be easily assembled and taken apart by unskilled labor for inspection or repairs.

Assuming the device to be constructed 85 as described and assembled in the ignition system of an engine, when the engine is in operation, the shaft 18 is revolved and carries the contact roller around with it. The casing or housing being stationary and the 90 lever 17 urged to retain the roller 21 in contact with the ring, said roller moves over the surface of the ring and intermittently engages the contact members 7. The contact members 7 forming one terminal of the 95 circuit and the ground the other terminal, a circuit is closed whenever the roller engages one of the contact members 7 and the desired ignition occurs.

While the present construction affords 100 slight opportunity for uneven wear of the contacts or segment blocks, should it be necessary to replace one of the contacts or blocks, the replacement may be effected without disturbing the entire timer and 105 without the loss incident to replacement of an entire ring.

It is also apparent that the tension of the movable contact members is uniform throughout the ring and that the continuous smooth surface avoids hammering and uneven wear.

What I claim and desire to secure by Letters-Patent is:

1. A timer comprising a casing, an insulating ring within the casing consisting of a plurality of spaced segments, contacts of channel form within which the ends of the segments are received, and means for securing the contacts to the casing. 115

2. A timer comprising a casing, an insulating ring within the casing consisting of a plurality of aligning segments, each of which is provided with a terminal offset portion, channel-shaped contact members engaging the offset portions of adjacent segments, bolts pivoted to the channel members and projecting through openings in the casing, and clamping nuts for engagement with the bolts. 120 125 130

3. A timer comprising a casing having openings about the periphery thereof, an insulating ring consisting of a plurality of segments, the ends of which are spaced 5 apart but overlap the edges of the openings, channel contact members within which the ends of the segments are received whereby the contact members serve as clamps to exert pressure against the segments in an 10 outward direction, complementary clamping members extending within the openings in the casing and engaging the outer face of the casing, and means for connecting the contacts and complementary clamping 15 members together.

4. A timer comprising a casing, an insulating ring within the casing consisting of spaced, segmental, interchangeable members, contact members for clamping the segments

to the casing, said contact members being 20 of channel form and interchangeable one with another, eye bolts swingingly connected to the channel members and projectable through openings in the casing, and clamping nuts for the eye bolts.

5. A timer comprising a casing, a plurality of aligning segments, each a duplicate of another and provided with terminal offset portions, a plurality of segment-clamping contacts, each contact being a duplicate of the other and consisting of a channel member having a threaded bolt swingingly connected thereto, and a nut for engaging the threaded portion of the bolt.

In testimony whereof I affix my signature.

ARTHUR W. CAPS.
